UNITED STATES PATENT OFFICE.

JOHN W. BAILEY, OF NEW YORK, N. Y., ASSIGNOR, BY MESNE ASSIGNMENTS, TO UNITED LEAD COMPANY, A CORPORATION OF NEW JERSEY.

APPARATUS FOR MAKING WHITE LEAD.

No. 823,097.

Specification of Letters Patent.

Patented June 12, 1906.

Application filed September 13, 1902, Serial No. 123,205.

To all whom it may concern:

Be it known that I, JOHN W. BAILEY, a citizen of the United States, and a resident of the city, county, and State of New York, have invented a new and useful Apparatus for Making White Lead or a Similar Product, of which the following is a specification.

My invention relates to an apparatus for making white lead, the present invention being more particularly addressed to one embodiment of the apparatus forming the subject-matter of an application filed August 1, 1900, Serial No. 25,503. The present embodiment of the apparatus is also designed to carry out the method of making white lead which forms the subject-matter of an application filed January 29, 1901, Serial No. 45,209.

My invention has for an object to provide a apparatus whereby the several steps of the process may be carried out expeditiously and with a minimum expenditure of labor.

It is also an object of my invention to provide an apparatus which is simple in construction and which may be manipulated with certainty and ease and which nevertheless is capable of treating a great quantity of material in a given time and space, also to provide an apparatus all parts of which are readily accessible for cleaning and repairing.

To this end my invention consists in the combination in a machine of the character referred to of a corroding-chamber, means adapted to form a support for the comminuted lead in the corroding-chamber, and mechanism independent of the corroding-chamber for advancing said supporting means into the corroding-chamber. In the best form of the invention the support for the comminuted lead consists of a plurality of trays which are adapted to slide on suitable ways in the corroding-chamber.

My invention also consists in the combination in such an apparatus of mechanism for advancing the supports into the corroding-chamber and means for feeding the comminuted lead onto the supports as they are being advanced into the corroding-chamber. In the best form of the apparatus the means for feeding the comminuted lead onto the supports consists of a device for comminuting the lead so that it may be maintained in an uncompacted condition.

My invention also consists in the combination in such an apparatus of a corroding-

chamber adapted to receive a plurality of supports for the comminuted lead, one above another, and mechanism for advancing said supports into the corroding-chamber, said mechanism being adjustable vertically so as to deliver the supports into the corroding-chamber one above another.

My invention also consists in the combination in such an apparatus of a corroding-chamber adapted to support a plurality of tiers of trays one above another, mechanism for advancing a series of trays in succession onto each of said ways, said mechanism consisting of a vertically-adjustable frame having guides for the trays and means for pushing the trays from said guides onto the ways in the corroding-chamber. In the best form of the apparatus the means for pushing the trays into the corroding-chamber consists of endless chains mounted on said frame and having pushers adapted to engage the trays.

My invention also consists in the combination in such an apparatus of a corroding-chamber which may be open at both ends and adapted to receive a line of trays, and mechanism for pushing the trays into one end of the corroding-chamber, whereby a line of trays in the corroding-chamber is delivered from one end thereof when a new line of trays is advanced into the opposite end.

My invention also consists in the combination in such an apparatus of a plurality of corroding-chambers arranged side by side, each adapted to receive a support for the comminuted lead, and mechanism for advancing the supports into the corroding-chambers, and a carriage on which said mechanism is mounted, so that it may be brought into co-operative relation with each of the corroding-chambers.

My invention also consists in the combination of two series of corroding-chambers, the corroding-chambers in each series being arranged side by side and adapted to be opened at each end, a mechanism for advancing the supports for the comminuted lead into the corroding-chambers of each series, said mechanisms being so mounted that they may be brought into co-operative relation with each of the corroding-chambers of the respective series, and a suitable washing mechanism located between the two series of corroding-chambers and adapted to receive the trays delivered therefrom.

My invention also consists in certain other features and combinations shown in the drawings and hereinafter more fully described.

5 The accompanying drawings, which are referred to herein and form a part hereof, illustrate one form of my present invention and serve, in connection with the description herein, to explain the principles thereof and the 10 best mode contemplated by me of carrying those principles into effect.

Of the drawings, Figure 1 is a diagrammatic plan view illustrating the relative arrangement of the parts forming the complete apparatus. Fig. 2 is a side elevation of 15 one of the mechanisms for advancing the supports in the corroding-chambers, together with the carriage upon which said mechanism is mounted. Fig. 3 is a vertical longitudinal section of the same. Fig. 4 is an end 20 view of the same, certain parts of the device being shown in section to more clearly illustrate certain details; and Fig. 5 is a sectional plan view illustrating certain details of the 25 mechanism.

Like reference-numerals refer to like parts wherever they appear throughout the several views.

Referring to the drawings in detail and at 30 first to the general view of the apparatus illustrated in Fig. 1, the two sets of corroding-chambers are represented by numerals 1 and 2, respectively, the corroding-chambers in each set being, as shown, for convenience arranged in pairs. The respective pairs of corroding-chambers are separated by alleys 3 and 4, in which the various pipes for supplying corroding gases and vapors to the corroding-chambers are arranged. Each of 35 40 the corroding-chambers is constructed to be opened at each end, and the two sets of corroding-chambers are oppositely arranged with relation to each other, so that one end of each corroding-chamber opens into the 45 space between the sets. At each of the farther or outer ends of the sets of corroding-chambers is arranged a suitable mechanism, generally indicated by the numeral 5, for advancing the supports for the comminuted 50 lead into the respective corroding-chambers, this mechanism being preferably mounted independently of the corroding-chambers upon suitable carriages 6, so that the mechanism may be successively arranged in coöperative relation with each of the corroding-chambers of the respective sets. 7 indicates 55 suitable tracks, said tracks running transversely to the ends of the corroding-chambers, as shown. In the space between the 60 two sets of corroding-chambers is arranged a device adapted to receive the corroded product as it is discharged from the inner or adjacent ends of the corroding-chambers. As shown, this device consists of a washing-machine 65 8, adapted to receive the supports as

they are delivered from the corroding-chambers and remove the corroded product therefrom. The specific construction of this washing-machine forms no part of my present invention. As indicated in the drawings, it consists of a platform 9, on which the supports containing the corroded product are received, and an endless conveyer 10 for advancing the supports beneath a series of scrubbing devices 11. After passing the scrubbing devices 11 the supports are delivered on a suitable carrying device, the same, as shown, consisting of a car 12, which is mounted upon a track 13, extending in both directions along the sides of the corroding-chambers and transversely outside of and parallel with the tracks 7, so that the supports may be readily transferred to either of the mechanisms 5 for advancing the same into the corroding-chamber with a new charge of comminuted lead. The corroded product, which is removed from the supports by the scrubbers 11, is carried to the opposite end of the machine, where it is received by a screening device 14, from which it passes, together with the water in which it is suspended, to suitable settling-tanks. (Not shown.)

The details of the mechanism for advancing the supports into the corroding-chambers are illustrated in detail in Figs. 2 to 5, inclusive, and will now be specifically described. In the embodiment of this feature of the apparatus illustrated the carriage 6 consists of a base-frame 15, substantially rectangular in form and carrying at its four corners suitable standards 16. These standards 16 are hollow, (see Fig. 4,) the same being constructed to receive corresponding tubular uprights 17, which carry at their upper ends a rectangular frame 18. Suspended from the frame 18 by means of the vertical posts 19 is a similar frame 20, and suspended from the frame 20 by the posts 21 is a lower frame consisting of longitudinal bars 22 and transverse girders 23, the latter being extended, as shown in Fig. 4, and provided with grooves adapted to engage the guiding-ribs 24, provided on each of the standards 16. Mounted on the side bars 22 by means of the two sets of brackets 25 and 26 are suitable upper and lower guide-rails 27 and 28, adapted to receive the supports 29 for the comminuted lead. The supports 29 preferably and as shown consist of suitable trays adapted when placed end to end to form a continuous reticulated support, on which the comminuted lead may be uniformly subjected to the action of the corroding-gases in the corroding-chamber. As shown, each of these trays consists of a series of parallel bars 29, which are arranged to extend transversely of the advancing mechanism and of the corroding-chambers, said bars being secured at their opposite ends by the longitudinal bars 30 and 31. Any suitable means may be provided

for advancing the trays along the guides 27 and 28 and onto the ways 32 in the corrodng-chamber. As shown, this means consist of a pair of endless chains 33, which are mounted 5 near the ends of suitable transverse shafts 34, journaled in the side bars 22. The upper stretches of the two chains are arranged opposite the space between the guides 27 and 28, and the two chains are connected at suitable intervals by means of transverse pushers which, as shown, consist of angle-bars 35, adapted to pass between the guides 27 and 28 and engage the rear ends of the successive trays.

15 In order that the guides 27 and 28, together with the parts coöperating therewith, may be adjusted vertically in order to bring them into coöperative relation with the various ways in the corrodng-chambers, suitable means are provided to raise and lower the posts 17, together with the parts suspended therefrom. The means shown consist of a series of vertical screw-threaded shafts 36, centrally located in the standards

25 16 and adapted to engage suitable nuts 37, carried by the lower ends of the post 17. Any suitable means may be provided for turning the shafts 36 in unison. As shown, each of the shafts is provided at its lower end with a beveled gear 38, which gears are adapted to mesh with corresponding beveled gears 39. The beveled gears 39 are mounted on transverse shafts, those at the forward end of the machine being fixed to shaft 40 and those at 30 the rear end of the machine to the shaft 41. The two shafts 40 and 41 are connected to rotate in unison by a chain 42, mounted on suitable sprockets 43 and 44. The shaft 40 is driven by chain 45, which receives motion

40 from a short transverse shaft 46, mounted at an intermediate point on the base-frame 15 and journaled at one end on one of the side bars of the frame 15 and at the other end on an intermediate bar 47 of said frame. The shaft 46 receives motion from the power-shaft 48, which may be driven by any suitable motor by chains 49 and 50, which are mounted on suitable sprockets on the shafts 46 and 48 and an intermediate shaft 51. In 45 order that the power-shaft 48 and the intermediate shaft 51 may be rotated independently of the shaft 46 for a purpose presently to be explained, a suitable disconnecting device is provided between the shafts 46 and 51.

50 55 As shown, the disconnecting device consists of a clutch 52, arranged between the shaft 46 and the spocket-wheel which receives motion from the chain 49. The clutch 52 may be operated by any suitable means, as by a hand-lever 53.

The chains 33 may be driven from the power-shaft 48 by any suitable means. As shown, the shaft 34 is driven from an intermediate shaft 54 by a pair of chains 55 and 65 56, which are mounted on suitable sprock-

ets, arranged with the outer ends of each of said shafts. The shaft 54 is journaled in the side bars 22 and is provided at one end with a worm-wheel 57, which is adapted to mesh with a suitable worm 58. In order that the pushing mechanism carried by the bars 22 may be raised and lowered without interrupting the driving connections for the chains 33, the worm 58 is loosely keyed to a vertical shaft 59, which is adapted to slide 70 loosely through the bearings 60 and 61 on the bar 22, between which bearings the worm 58 is confined. The shaft 59 is journaled at its lower end in a suitable bracket 62, carried by the base-frame 15, and is geared to the 80 shaft 51 by suitable beveled gears 63. In order that the raising and lowering mechanism may be operated independently of the pushing-chains 33, a suitable disconnecting device is arranged between the shaft 58 and 85 the shaft 59. As shown, a clutch 64 is located between the shaft 51 and the gears 63, which clutch may be operated by a suitable lever 64.

In order that the comminuted lead may be 90 fed onto the trays as they are advanced into the corrodng-chamber and that it may be fed thereto in an uncompacted condition, the means whereby the lead is comminuted is preferably carried with the tray-advancing mechanism and is so arranged as to feed the comminuted lead directly onto the trays. To this end a melting-pot 65, from which the molten lead is delivered in suitable fine streams through a suitable perforated plate 100 66, is mounted on the frame 20. Preferably and as shown the pot is arranged at the end of the frame farthest from the corrodng-chambers, and the delivery-spouts, with the perforated plates 66, are so arranged as to deliver the lead onto the trays as they pass from the guides 27 and 28 into the corrodng-chamber. 67 represents suitable burners by 105 which the melting-pot is heated. The frame 20 is provided at its opposite sides with suitable platforms 68, having hand-rails 69. For the purpose of guiding the outer streams of lead onto the trays suitable shields 70 are provided at the sides above and at the forward end of the guides 27.

110 When the lead in any of the corrodng-chambers has been completely corroded, the ends of the chamber are opened and the mechanism for advancing the trays into the chamber is brought into coöperative relation therewith. The melting-pot having 115 been suitably heated and the guides 27 and 28 having been brought into alinement with either the upper or the lower set of ways 32, the pushing-chains 33 are started. The trays 120 which are supplied to the outer or feed ends of the guides by hand from one of the cars 12 are then advanced into the corrodng-chamber, carrying in with them a suitable layer of the comminuted metal. As the new line of 125 130

trays are advanced into the corroding-chamber the trays which contain the corroded product are pushed therethrough and are delivered one by one at the opposite end of the 5 chamber, from whence they are transferred to the platform 9 of the washing-machine. While the trays containing the product are usually transferred to the washing-machine by hand, it is obvious that a suitable carrying 10 device may be provided for this purpose, if desired. When the new line of trays is advanced the full length of the corroding-chamber, the advancing mechanism is stopped and is moved vertically into line 15 with the next tier of trays, these operations being accomplished by suitable manipulation of the clutches 52 and 64. The advancing mechanism is then set into motion, and the above-described operations are repeated. 20 When the corroding-chamber is completely filled with a new charge of comminuted lead, it is closed up and the corroding-gases are admitted thereto, the advancing mechanism being moved by means of a carriage 6 to 25 another corroding-chamber in which the product has been completely corroded. By mounting the means for comminuting the lead on the vertically-adjustable frame the proper coöperative relation between the 30 comminuting means and the trays as they are being advanced into the corroding-chambers is always maintained, so that the comminuted lead is delivered in precisely the same condition upon each of the tiers of 35 trays. In this way the entire charge of metal in each corroding-chamber is uniformly subjected to the action of the corroding-gases and an even corrosion of the metal is insured. 40 My invention in its broader aspects is not limited to the precise construction shown, nor to the particular construction by which it is carried into effect, as many changes may be made in the construction without departing from the main principles of the invention and without sacrificing its chief advantages. 45

What I claim as new, and desire to secure by Letters Patent, is—

1. In an apparatus for making white lead or similar product, the combination with a 50 corroding-chamber of means adapted to form a support for the comminuted lead in the corroding-chamber, and means mounted independently of the corroding-chamber for advancing said supporting means into the corroding-chamber.
2. In an apparatus for making white lead or similar product, the combination with a corroding-chamber of means adapted to form a 60 support for the comminuted lead in the corroding-chamber, mechanism mounted independently of the corroding-chamber for advancing said supporting means into the corroding-chamber, and means for feeding com- 65 minuted lead onto said supporting means as

it is being advanced into the corroding-chamber.

3. In an apparatus for making white lead or similar product, the combination with a corroding-chamber of a plurality of trays 70 adapted to form a substantially continuous support for the comminuted lead in the corroding-chamber, and mechanism for advancing said trays into the corroding-chamber, said mechanism being adjustable to advance 75 the supports into different parts of the corroding-chamber.

4. In an apparatus for making white lead or similar product, the combination with a corroding-chamber of a plurality of trays 80 adapted to form a substantially continuous support for the comminuted lead in the corroding-chamber, mechanism for advancing said trays into the corroding-chamber, and means for feeding comminuted lead onto the 85 trays as they are being advanced into the corroding-chamber.

5. In an apparatus for making white lead or similar product, the combination with a corroding-chamber of means adapted to form 90 a support for the comminuted lead in the corroding-chamber, means mounted independently of the corroding-chamber for advancing said supporting means into the corroding-chamber, and means for comminuting the 95 lead, said comminuting means being arranged to feed the comminuted lead onto said supporting means as it is being advanced into the corroding-chamber.

6. In an apparatus for making white lead 100 or similar product, the combination with a corroding-chamber of a plurality of trays adapted to form a substantially continuous support for the comminuted lead in the corroding-chamber, mechanism for advancing 105 said trays into the corroding-chamber, and means for comminuting the lead, said comminuting means being arranged to feed the comminuted lead onto the trays as they are being advanced into the corroding-chamber. 110

7. In an apparatus for making white lead or similar product, the combination with a corroding-chamber adapted to receive a plurality of supports for the comminuted lead one above another, mechanism for advancing 115 said supports into the corroding-chamber, said mechanism being adjustable to advance the supports into the corroding-chamber one above another.

8. In an apparatus for making white lead 120 or a similar product, the combination with a corroding-chamber adapted to receive a plurality of supports for the comminuted lead one above another, mechanism for advancing 125 said supports into the corroding-chamber, said mechanism being vertically adjustable independent of the corroding-chamber to advance the supports into the corroding-chamber one above another.

9. In an apparatus for making white lead 130

- or similar product, the combination with a corrodng-chamber adapted to receive a plurality of supports for the comminuted lead one above another, mechanism for advancing said supports into the corrodng-chamber, said mechanism being adjustable to deliver the supports into the corrodng-chamber one above another, and means for feeding comminuted lead onto said supports as they are being advanced into the corrodng-chamber.
10. In an apparatus for making white lead or similar products the combination with a corrodng-chamber adapted to receive a plurality of supports for the comminuted lead, one above another, mechanism for advancing said supports into the corrodng-chamber, said mechanism being vertically adjustable independent of the corrodng-chamber to deliver the supports into the corrodng-chamber one above another, and means for feeding comminuted lead onto said supports as they are being advanced into the corrodng-chamber, said feeding means being vertically adjustable with the mechanism for advancing the supports into the corrodng-chamber.
11. In an apparatus for making white lead or similar products, the combination with a corrodng-chamber adapted to receive a plurality of supports for the comminuted lead one above another, mechanism for advancing said supports into the corrodng-chamber, said mechanism being adjustable to deliver the supports into the corrodng-chamber one above another, means for comminuting the lead, said comminuting means being arranged to feed the comminuted lead onto said supports as they are being advanced into the corrodng-chamber.
12. In an apparatus for making white lead or similar product, the combination with a corrodng-chamber adapted to receive a plurality of supports for the comminuted lead one above another, mechanism for advancing said supports into the corrodng-chamber, said mechanism being vertically adjustable independent of the corrodng-chamber to deliver the supports into the corrodng-chamber one above another, and means for comminuting the lead, said comminuting means being vertically adjustable with the mechanism for advancing the supports and arranged to feed the lead onto said supports as they are being advanced into the corrodng-chamber.
13. In an apparatus for making white lead or similar product, the combination with a corrodng-chamber having a plurality of ways adapted to support a plurality of tiers of trays one above another, mechanism for advancing a series of trays in succession onto each of said ways, said mechanism including a vertically-adjustable frame having guides for the trays, and having means for pushing the trays from said guides onto the ways in the corrodng-chamber.
14. In an apparatus for making white lead or similar product, the combination with a corrodng-chamber having a plurality of ways adapted to support a plurality of tiers of trays one above another, mechanism for advancing a series of trays in succession onto each of said ways, said mechanism consisting of a vertically-adjustable frame having guides for the trays, and endless chains mounted on said frame and having pushers adapted to engage the trays.
15. In an apparatus for making white lead or similar product, the combination with a corrodng-chamber having a plurality of ways adapted to support a plurality of tiers of trays one above another, mechanism for advancing a series of trays in succession onto each of said ways, said mechanism consisting of a vertically-adjustable frame having guides for the trays, means for pushing the trays from said guides onto the ways in the corrodng-chamber, and means for feeding comminuted lead onto said trays as they are being advanced into the corrodng-chamber.
16. In an apparatus for making white lead or similar product, the combination with a corrodng-chamber having a plurality of ways adapted to support a plurality of tiers of trays one above another, mechanism for advancing a series of trays in succession onto each of said ways, said mechanism consisting of a vertically-adjustable frame having guides for the trays, means for pushing the trays from said guides onto the ways in the corrodng-chamber, and means for comminuting the lead, said comminuting means being arranged to feed the comminuted lead onto the trays as they are being advanced into the corrodng-chamber.
17. In an apparatus for making white lead or similar product, the combination with a corrodng-chamber having a plurality of ways adapted to support a plurality of tiers of trays one above another, mechanism for advancing a series of trays in succession onto each of said ways, said mechanism consisting of a vertically-adjustable frame having guides for the trays, means for pushing the trays from said guides onto the ways in the corrodng-chamber, and means for comminuting the lead, said comminuting means consisting of a melting-pot having a plurality of fine openings through which the molten lead is discharged, said melting-pot being arranged to deliver the lead onto the trays as they are being advanced into the corrodng-chamber.
18. In an apparatus for making white lead or similar product, the combination with a corrodng-chamber open at both ends, means for supporting a line of trays in said chamber and mechanism for advancing the trays one by one into one end of the chamber, whereby when a new line of trays is advanced into one

- end of the corroding-chamber, the trays in the chamber are by means of the advancing trays delivered at the opposite end thereof. 60
19. In an apparatus for making white lead or similar product, the combination with a corroding-chamber open at both ends, means for supporting a line of trays in said chamber and mechanism for advancing the trays one by one into one end of the chamber, whereby when a new line of trays is advanced into one end of the corroding-chamber, the trays in the chamber are delivered at the opposite end thereof, and means for feeding comminuted lead onto the trays as they are advanced into the corroding-chamber. 65
20. In an apparatus for making white lead or similar product, the combination with a corroding-chamber open at both ends, of means for supporting a line of trays in said chamber, and mechanism for advancing the trays one by one into one end of the chamber, whereby when a new line of trays is advanced into one end of the corroding-chamber, the trays in the chamber are delivered at the opposite end thereof, and means for comminuting the lead, said comminuting means being arranged to feed the comminuted lead onto the trays as they are advanced into the corroding-chamber. 70
21. In an apparatus for making white lead or similar product, the combination with a corroding-chamber open at both ends and provided with means for supporting a plurality of tiers of trays one above another, of mechanism for advancing the trays one by one into one end of the chamber, said mechanism being vertically adjustable to advance the trays onto the various supports in the corroding-chamber whereby the tiers of trays in the corroding-chamber will be delivered at one end thereof as the new tiers are advanced into the other end. 75
22. In an apparatus for making white lead, or similar product, the combination of a plurality of corroding-chambers arranged side by side, each adapted to receive a support for the comminuted lead, mechanism for advancing the supports into the corroding-chambers, and a carriage on which said mechanism is mounted whereby said mechanism may be brought into coöperative relation with each of the corroding-chambers. 80
23. In an apparatus for making white lead or similar product, the combination with a plurality of corroding-chambers arranged side by side, each adapted to receive a support for the comminuted lead, mechanism for advancing the support into the corroding- 85
- chamber, means for feeding the comminuted lead onto the support as it is advanced into the corroding-chamber, and a carriage on which the support-advancing mechanism and the feeding means are mounted, whereby said parts may be brought into coöperative relation with each of the corroding-chambers. 90
24. In an apparatus for making white lead or similar product, the combination of a plurality of corroding-chambers arranged side by side, each having a plurality of ways adapted to receive supports for the comminuted lead, mechanism for advancing the supports into the corroding-chamber, and a carriage on which said mechanism is mounted so as to be vertically adjustable whereby said mechanism may be brought into coöperative relation with the various ways in each corroding-chamber. 95
25. In an apparatus for making white lead or similar product, the combination with a plurality of corroding-chambers arranged side by side, each having a plurality of ways adapted to receive supports for the comminuted lead, mechanism for advancing said supports into the corroding-chambers, means for feeding comminuted lead onto the supports as they are being advanced into the corroding-chambers, and a carriage on which said support-advancing mechanism and said feeding means are adjustably mounted whereby said parts may be brought into coöperative relation with the various ways in each corroding-chamber. 100
26. In an apparatus for making white lead or similar product, the combination with two series of corroding-chambers, each series consisting of a plurality of corroding-chambers arranged side by side and adapted to receive supports for the comminuted lead, the two series of corroding-chambers being oppositely arranged with relation to each other and suitably separated, mechanism for advancing the supports into each set of corroding-chambers, said mechanism being so arranged with relation to the sets of corroding-chambers that the supports are delivered from the corroding-chambers into the space between them, and a washing device located between the corroding-chambers for receiving the supports delivered therefrom. 105
